(57) **CLAIM**

The ornamental design for the equipment for acrobatic sports as shown and described.

DESCRIPTION

Fig. 4.1 is a perspective view of the equipment for acrobatic sports.

Fig. 4.2 is another perspective view thereof.

Fig. 4.3 is a front elevation view thereof.

Fig. 4.4 is a back elevation view thereof.

Fig. 4.5 is a right side elevation view thereof.

Fig. 4.6 is a left side elevation view thereof.

Fig. 4.7 is a top plan view thereof.

The broken lines in the drawings depict portions of the equipment for acrobatic sports and form no part of the claimed design.
